UNITED STATES PATENT OFFICE.

HERMAN STAUB, OF WYOMISSING, PENNSYLVANIA, ASSIGNOR TO TEXTILE MACHINE WORKS, OF WYOMISSING, PENNSYLVANIA, A CORPORATION OF PENNSYLVANIA.

CARRIER DRIVE FOR LACE BRAIDERS.

Application filed September 5, 1923. Serial No. 661,012.

To all whom it may concern:

Be it known that I, HERMAN STAUB, a citizen of the United States, residing at Wyomissing, in the county of Berks and 5 State of Pennsylvania, have invented certain new and useful Improvements in Carrier Drives for Lace Braiders, of which the following is a specification.

My invention relates to lace-braiding machines, and particularly to improved carrier-drive mechanism therefor as herein-after fully described in connection with the accompanying drawings and the novel features of which are clearly defined in the 15 subjoined claims.

The inner walls of the carrier race-way circles of ordinary braiding machines have heretofore been formed by quoit plates fixed to the central drive-gear posts in the plane 20 of the main plate and so shaped as to permit of the course of the driven carriers being properly directed at the circular intersections. In lace braiders however, where the carriers are required to repeatedly traverse the same race-circle, these quoit plates have been made to serve as carrier drivers, in addition to serving in connection with the main race-way plate, to support the moving carriers. In my improved construction I provide for dividing these heretofore combined functions, by employing fixed quoit plates of true circular contour arranged in the plane of the main race-way plate and each adapted to serve as a fixed 25 carrier support and a fixed race-circle wall, in connection with a separate drive disc arranged below said fixed quoit plate and provided with carrier-engaging horns and with rest recesses adapted to cooperated 30 with the fixed quoit and additional carrier-guide means, in properly directing the carrier at the race-circle intersections; this improved construction not only providing an advantageously rigid supporting base for 35 the moving carriers, but enabling the use of simplified carrier driving and locking 40 means as hereinbefore described.

Fig. 1 is a partially sectional view on the line 1—1 of Fig. 3 of a portion of a braiding machine showing my improved drive mechanism in preferred form.

Fig. 2 is a cross-sectional view taken on the line 2—2 of Fig. 1.

Fig. 3 is a partly sectional plan view 55 showing several race-circles and posts; one

of the posts being shown in section on the line 3—3 of Figs. 1 and 2 to clearly reveal the carrier-drive-disc; another post being in section on the line 3^a—3^a of Fig. 2 with the carrier-guide clutch lever fully shown; 60 and the mechanism on an intermediate post being shown in operative relation to a carrier pin and an adjacent drive gear.

Fig. 4 is a bottom view of one of the fixed circular quoits showing its stop recesses. 65

The drawing shows the usual top and bottom plates 5 and 6 of a braiding machine, with intersecting race-circle openings 7, 7, 7 forming the outer walls of the race-way, and central posts 8, 8, 8 fixed to the 70 bottom plate and having mounted thereon respectively the usual intermeshing drive-gears 10.

In my improved construction the fixed inner wall of each race-circle is formed around 75 the post 8 by means of a circular disc or quoit 15 which is fixedly secured to the top of the post in the plane of the top plate 5; thus providing in connection with the latter a steady support for the flanged foot 80 16^a of the moving carrier 16; the race-way thus formed, however, providing no means for directing the movement of the carrier at the intersection of the race-circles so as to cause repeated rotations around the post 85 center as is required in lace-braiding.

The intermittent driving of the carrier, as well as the locking of same in determined position when it is freed from the continuously rotated drive gear 10, is effected by 90 means of a carrier-drive device on the post 8; said device comprising a drive disc 20 having horns 20^a for engaging the depending carrier pins 16^b, and being adapted to be moved into engagement with the fixed quoit 15 95 whenever it is disengaged from the gear 10, so as to be locked thereby. This carrier-drive disc 20, as shown, forms part of a clutch sleeve which is rotatably mounted on the post 8 and is movable axially thereon 100 by means of a pattern-operated clutch lever 30 in known manner, so as to cause engagement or disengagement of its lower teeth 20^b with the teeth 10^a of the drive gear 10; and it is also provided with locking-teeth 105 or projections 21 adapted to engage locking recesses 15^a in said fixed quoit 15 when the disc 20 is moved upward to disengage the drive gear 10.

Each drive disc 20 thus mounted below 110

the fixed quoit plate 15, has its opposite horns 20^a formed in connection with carrier-rest recesses 20^c such as are shown in the rotary quoit plates of Rahm Patent No. 1,256,038 of Feb. 12, 1918; the depending pins 16^b of the carriers 16 being in my improved construction similarly engaged by the separate depressed drive disc 20, and being brought to rest at each half revolution

10 in the recesses 20^c thereof.

Each carrier-drive disc 20 with its integral clutch-sleeve, is moved axially by means of a clutch lever arm 30, fixed as heretofore to an automatically operated vertically-guided clutch bar 31^a having a spring 32 whereby the sleeve is normally raised out of engagement with the drive gear 10, while a jacquard or other pattern mechanism determinedly lowers the same into driving engagement with the gear 10. When thus lowered the disc 20, as shown, is thrown out of locking engagement with the locking recesses 15^c of the fixed quoit 15, while when raised it engages the latter to definitely stop its relative action on an engaged carrier pin 16^b.

In Fig. 3 one of these carrier pins 16^b is shown at rest after a half rotation, in the space provided between the adjacent drive discs 20, 20 by the respective recesses 20^c, 20^c in the latter; the rotation of the drive disc 20 to the right of said pin 16^b having been stopped by the raising of disc 20 out of engagement with the drive gear 10 and into locking engagement with the fixed quoit 15 above it, while the drive disc 20 to the left of it is being rotated as indicated by the arrow. In order to position the depending carrier pin 16^b in the rest recesses so that it will be properly engaged by the horn 20^a of said rotating disc, it is necessary to provide a guide therefor which will place it directly in the path of said horn 20^a when rotation of the drive disc to the right is stopped. As shown this special carrier guide is formed by integral wings 31, 31 on the clutch lever 30, which wings overlap the rest recess 20^c when the lever is moved upward with the corresponding drive disc 20, so as to prevent the carrier pin 16^b from getting more or less out of the path of the rotating horn 20^a; one or other of said carrier guide wings as required, being beveled as indicated at 31^a so that it will push said pin into proper position in the recess as its drive disc 20 is being raised into its stop engagement with fixed quoit 15, as well as prevent its movement out of the path by contact of the rotating horn.

60 It will be seen that my invention provides

for satisfactorily effecting the special carrier movements commonly required in lace braiders, while at the same time providing a fixed quoit for steadily supporting the travelling carriers and a simply constructed 65 and operated mechanism.

What I claim is:

1. In a lace-making machine comprising a race-way plate having intersecting race-circle openings; a central post for each race-circle having mounted thereon a fixed disc-locking quoit, a rotary drive gear, and a carrier-operating drive-disc movable into and out of engagement with said drive gear and fixed quoit to alternately drive and lock 75 the same; and a movable carrier-guide device operatively positioned only when said drive disc is moved into locking engagement with said fixed quoit.

2. In a lace-making machine comprising a race-way plate having intersecting race-circle openings; a central post for each race-circle having mounted thereon a fixed disc-locking quoit, a rotary drive gear, and a carrier-operating drive-disc movable into 85 and out of engagement with said drive gear and fixed quoit to alternately drive and lock the same; and a clutch lever having a carrier-guide portion operative only when said drive disc is moved into locking engagement with said fixed quoit.

3. In a lace-making machine comprising a race-way plate having intersecting race-circle openings, and a central post for each race-circle provided with a fixed disc-locking quoit and a rotary drive gear; a drive-disc formed with carrier-engaging horns and rest recesses and movable into and out of engagement with said drive gear and fixed quoit to alternately drive and lock the 100 same; and shifting means for said drive disc comprising a carrier-guide operatively positioned relative to an adjacent rest-recess when said disc is moved into locking engagement with said fixed quoit.

4. In a lace-making machine comprising a race-way plate having intersecting race-circle openings; a central post for each race-circle having mounted thereon a fixed disc-locking quoit, a rotary drive gear, and a carrier-operating drive-disc movable into 110 and out of engagement with said drive gear and fixed quoit to alternately drive and lock the same; and a movable carrier-guide device operatively positioned only when said drive disc is moved into locking engagement with said fixed quoit, said guide device having a beveled carrier-contacting face.

In testimony whereof I affix my signature,

HERMAN STAUB.
